Specification for Design.

Patented Nov. 21, 1916.

Application filed June 30, 1916. Serial No. 106,982. Term of patent 14 years.

To all whom it may concern:

Be it known that I, RAY A. GRAHAM, a citizen of the United States, and a resident of the city of Evansville, county of Vanderburgh, and State of Indiana, have invented a certain new, original, and ornamental Design for a Bottle, of which the following is a specification, reference being had to the accompanying drawing, forming part thereof.

Figure 1 is a perspective view of a bottle illustrating said design. Fig. 2 is a bottom plan view, showing the bottom of said bottle. Fig. 3 is a horizontal transverse section on

the line 3, 3 of Fig. 1, showing the conformation of said bottle at said line.

I claim:

The ornamental design for a bottle as shown.

In testimony whereof I have signed my name to this specification in the presence of two subscribing witnesses.

RAY A. GRAHAM.
